CLAIM

The ornamental design for a shining image lamp, as shown and described.

DESCRIPTION

FIG. 1 is a perspective view of the top, front, and right sides of a shining image lamp with the top partially extended; FIG. 2 is a perspective view of the shining image lamp of FIG. 1 with the top fully extended and the lower portion oriented to shine a first image;

FIG. 3 is a perspective view of the shining image lamp of FIG. 2 rotated ninety degrees, with the top fully extended and the lower portion oriented to shine a second image;

FIG. 4 is a perspective view of the shining image lamp of FIG. 3 rotated ninety degrees, with the top fully extended and the lower portion oriented to shine a third image; and,

FIG. 5 is a perspective view of the shining image lamp of FIG. 4 rotated ninety degrees, with the top fully extended and the lower portion oriented to shine a fourth image.

The broken lines shown on the drawings depict environment only and form no part of the claimed design.
